UNITED STATES PATENT OFFICE.

CLARENCE G. HENNEY, OF FAIRBURY, NEBRASKA; CHARLOTTE M. HENNEY, EXECUTRIX OF SAID CLARENCE G. HENNEY, DECEASED, ASSIGNOR TO FAIRBURY WINDMILL COMPANY, OF FAIRBURY, NEBRASKA, A CORPORATION OF NEBRASKA.

WINDMILL PULL-OUT.

Application filed July 22, 1924. Serial No. 727,554.

My invention relates to pull-out mechanisms for windmills of the type having a pivoted vane. My pull-out mechanism is designed particularly for use in connection with windmills having the gearing and oiling system described in my copending application, Serial Number 718,895, filed June 9, 1924, but it is adapted for use on any or all windmills of the general type.

10 In brief, the object of my invention is the provision of a pull-out mechanism which is entirely outside the lubricant container and the mast so that neither can interfere with or be interfered by the operation of the pull-out mechanism, and so that all parts of the pull-out mechanism are within easy access and plain sight at all times. Other objects will be referred to and discussed in greater detail in the following description.

20 Referring now to the drawings forming part of my application, and in which like numerals designate like parts in the description,

Figure 1 is a side elevation of the windmill head showing also a portion of my pull-out mechanism.

25 Figure 2 is a plan view of the parts shown in Figure 1.

Figure 3 is a view in perspective of the 30 upper portion of the windmill tower and of the mast, showing particularly the swivel mechanism whereby the pull-out chains and cords are made to operate entirely outside the tubular mast.

35 Figure 4 is a view in perspective of a portion of the collar surrounding the tubular mast at its upper extremity, and showing the guideway for the pull-out chain.

40 Figure 5 is a perspective view of one-half the upper portion of the swivel, showing both the inner and the outer members thereof.

Figure 6 is a perspective view of the entire lower portion of the swivel.

45 Figure 7 is a perspective view of the clamp surrounding the mast at a point below the swivel, and which cooperates with the swivel.

The windmill includes the usual tower 10 with the top casting 11 bolted thereto. The 50 top casting 11 carries the turntable 12 on a ball race and the turntable supports the working parts of the windmill. The main casting 13 serves both as an oil reservoir

and as a support for bearings and pivots of the drive shaft and of the vane. Underneath the main casting 13, either rigidly secured thereto or integral therewith, is a collar 14 surrounding the mast 15. In my preferred construction the collar comprises two parts 14^a and 14^b which have ears and registering apertures whereby they may be tightly clamped together and to the mast. The part 14^a is an integral part of the casting 13 and its inner surface is semicylindrical and of the same diameter as that of the mast. 55 The part 14^b is complementary to the part 14^a and is secured thereto by means of bolts and nuts or other suitable securing means. The collar 14 is clamped tightly on the mast 10 and when the parts are thus assembled the main casting 13 is in effect integral with the mast 15 and the collar 14. The mast 15 is rigidly secured in the turn table 12, so that the entire weight of the working parts of the windmill is carried on the turn table and 60 its ball race. The mast 15 passes through and is anchored in the spider 16 in such a way as to maintain the mast in perpendicular relation and to prevent endwise movement but at the same time permitting the mast 70 to turn.

The hood or cowl 17 covers the main casting 13 and the working parts of the windmill, its principal function being to prevent the entrance of water, dust and other foreign 75 matter into the lubricant container. The vane arm 18 is connected by means of the vertical pivot 19 to the main casting 13. In order to prevent the sagging of the vane and the vane arm 18, I provide a supporting 80 brace 20 which is connected to the vane arm at or near its forward extremity and indirectly to the casting as shown in Figure 1. The vane arm 18 is provided with a right angled projection 21 carrying a bumper 85 90 spring 22 at its free end. The spring 23 and its connections cooperate with the arm 21 to normally maintain the vane arm in substantial alignment with the main drive shaft 24.

The vane arm, while normally held by the spring 23 in a more or less fixed position, is otherwise free to swing through an arc of one quadrant. For controlling the movement of the vane and vane arm on its pivot, 105 I provide the chain 25 and the connections

hereinafter described. The forward end of the chain 25 is secured to the vane arm 18 at a point somewhat remote from the pivot 19. The sheave 26 is secured to the supporting bracket 27 and is spaced out of alignment with the vane arm 18 and on the side opposite the spring 23. The sheave 28, as shown in Figure 3 is mounted on a horizontal pivot in brackets which are secured to the main casting 13 in such position that the inner vertical tangent of the sheave will be just outside the outer surface of the mast 10.

Referring now to Figures 2, 3 and 4, it will be seen that the part 14^b of the clamp is provided with a passageway 29 which is outside the mast when the parts are in assembled relation. The turntable 12 is also provided with a vertical passageway as shown in Figure 3, which in the assembled windmill is in alignment with the passageway 29. The chain 25 passes over the sheaves 26 and 28 and thence down through the aligning passageways.

Secured to the mast 15 underneath the top casting 11 is a swivel which permits free oscillation or rotation on a vertical axis of the main casting 13 and the parts connected thereto, but which definitely limits the oscillation of the pull-out parts underneath the swivel. The collars 30 and 31 are both secured to rotate with the mast 15, but to prevent any possibility of slippage I provide a rod 32 which passes through aligning vertical apertures in the collars 30 and 31. The upper end of the rod 32 is anchored in the turntable 12, the lower end of the rod being anchored in the clamp 33 which tightly encircles the mast at a point below the swivel. The collars 30 and 31 are thus secured against independent rotation or oscillation but they are freely slideable on both the mast 15 and the rod 32, the lower limit of the sliding movement being determined by the position of the clamp 33. The collar 30 has an upwardly projecting hook 34 for securing the lower end of the chain 25.

Interlocked with the inner collars 30 and 31 are the outer collars 35 and 36. For convenience in assembling and when making adjustments and repairs, the outer collars are formed of semicircular halves, each half being provided with ears 37 having registering apertures for the reception of bolts or other suitable securing means. The outer collars are grooved on their inner peripheries, the grooves being adapted to receive the projecting annular webs on the outer peripheries of the inner collars, as shown in Figure 5. Each pair of collars therefore includes an inner collar which is slidably and non-rotatably mounted on the mast and an outer collar which is nonslidably and rotatably secured to the inner collar. The outer collars 35 and 36 are connected with each other by means of the rods 38 passing

through and secured in the apertures of the ears 37.

For actuating the pull-out mechanism from a convenient position near the pump platform, a pull-out cord or wire 39 is secured to the downwardly projecting pair of ears 37 of the collar 36. It will readily be seen that when downward tension is applied to the pull-out cord or wire 39, the entire swivel will be drawn downwardly and with it the lower end of the chain 25, the downward movement being limited by the clamp 33. The tension on the chain 25 causes the movement of the vane arm 18 on its pivot. The wire 39 may then be secured in the down position and when it is desired to again start the windmill it is only necessary to release the wire 39. When the pull-out wire 39 is released the spring 23 draws the vane arm 18 back into alignment with the axis of the wind wheel, the movement being transmitted through the chain 25 to draw the swivel upwardly to its elevated position. The opening movement of the vane arm 18 is stopped when the arm 21 strikes the casting 13 and the bumper spring 22 takes up the shock of the impact and thus prevents injury to the various parts. When the parts above the tower turn in the wind about the vertical axis, the chain 25 and the collars 30 and 31 are forced to move about the same vertical axis but the collars 35 and 36 remain practically stationary so that the pull-out wire 39 will not be wound and twisted on the mast. There necessarily is a certain degree of friction between the inner and outer collars of the swivel with the result that there is a limited amount of arcuate movement of the outer collars when the direction of the wind changes, but this arcuate movement is held within definite limits by the arm 40 secured in the downwardly projecting ear 41 of the collar 36, the arm 40 being of sufficient length to abut against two of the posts of the tower. The oscillation of the outer portion of the swivel is thus limited to an arc of less than a quadrant.

My invention does away entirely with the necessity of interference between the lubricating device and the pull-out mechanism since all parts of the pull-out mechanism are positioned entirely outside the lubricant chamber. All parts of the pull-out mechanism are moreover clearly visible from the ground so that the need of adjustments or repairs can be instantly recognized and located in time to prevent possible serious damage. When such adjustments or repairs are required, it will be found that all parts are within easy access and that the adjustments and repairs can be made without disassembling the windmill or any portions of the windmill.

It is evident that various changes, variations, and modifications might be resorted

to without departing from the spirit and scope of my invention and hence I do not wish to limit myself to the exact disclosures thereof.

Having thus described my invention in terms which will be readily understood by others skilled in the art to which it pertains, what I believe to be new and desire to secure by Letters Patent of the United States 10 is:—

1. In a windmill, an integral and seamless casing which is adapted to retain lubricating oil and which is adapted also to support the working parts of the windmill, and a clamp 15 for securing a downwardly projecting mast to the said casing, said clamp comprising two semicylindrical members, one only of said members being integral with said casing, and means for uniting said members in 20 clamping relation about the upper extremity of the mast, said clamp being positioned substantially beneath the center of mass of the casing with the working parts of the windmill secured thereto.

2. In a windmill, a casing for retaining lubricating oil and for supporting the working parts of the windmill, a vertically positioned tubular mast for supporting the said casing, a clamp for securing the casing to the tubular mast at its upper extremity, a vane pivotally secured to said casing, tension means for normally holding said vane in parallelism with the wheel shaft of the windmill, and manually operable means for causing said vane to swing on its pivot and out of its normal position, said last named means being positioned outside the mast and outside the casing, there being a passageway therefor between the clamp and the upper portion of the mast.

3. A windmill including a casing for supporting the working parts of the windmill and for retaining lubricant, a mast for supporting said casing, a collar on said casing and surrounding the upper extremity of said mast, and a manually operable pull-out for

controlling the operation of said windmill, said collar being provided with a passageway for said pull-out and said pull-out being positioned entirely outside said casing and 50 said mast.

4. A windmill including a mast for supporting the working parts of the windmill and a pull-out mechanism for manually controlling the operation of said windmill, said 55 pull-out mechanism including a collar surrounding and slidable on said mast, said collar being secured to the head of the windmill so as to rotate therewith about the said mast as an axis, a connection between said collar and the pull-out mechanism of the windmill, a second collar surrounding the first said collar and rotatable thereon, means projecting radially from said second collar for limiting in both directions the rotation 60 thereof, and a connection from said second collar extending downwardly whereby tension on said last named connection will cause the downward movement of both said collars on said mast to cause said first named connection to operate the pull-out mechanism of the windmill.

5. A windmill including a head with pull-out mechanism, a mast and a turntable, a collar surrounding said mast and slidably 75 and rotatable thereon, an abutment surrounding said mast for limiting the downward movement of said collar, a vertical rod passing through said turntable, collar and abutment for causing said collar and 80 abutment to be rotated in unison with said turntable, a connection from said collar to said pull-out mechanism, a second collar surrounding the first said collar and secured thereto so as to have axial movement thereon, means for limiting the axial movement of said second collar, and means for slidably moving said collars to actuate the pull-out mechanism.

In testimony whereof I affix my signature.

CLARENCE G. HENNEY.
